CAR DOOR

Gabriel Madland, Chicago, Ill., assignor, by mesne assignments, to The Youngstown Steel Door Company, Cleveland, Ohio, a corporation of Ohio

Application February 1, 1932, Serial No. 590,021

17 Claims. (Cl. 189—46)

This invention relates to car doors and concerns itself essentially with the construction of metallic doors which, in lowered position, are frictionally retained against movement and are capable of sliding movement in the elevated position, and with elevating and supporting mechanism for said doors.

It is an object of this invention to provide metallic doors of the lift type in which the parts of the lifting mechanism with exception of the operating lever are hidden.

A further object is the provision of metallic doors so modified or designed that lifting mechanism may be applied thereto with the moving parts thereof, excepting the operating lever, hidden from view and protected by the door.

A further object is to provide a metallic door having a horizontal corrugation adjacent an edge thereof, said corrugation adapted to receive an actuating bar of lifting and supporting mechanism applied to the door to protect said bar.

A further object is to provide novel elevating means for sliding car doors and novel means for connecting an operating lever included in said elevating means.

Other objects will become clear as the description of the invention proceeds.

In the drawings:

Figure 1 is a partial elevation of a lift door embodying the invention.

Figure 2 is an enlarged detail of the lower left hand portion of the door which is illustrated in lowered or normal position.

Figure 3 is a view similar to Figure 2, showing the door in elevated position.

Figure 4 is a vertical section taken on line 4—4 of Figure 1.

Figure 5 is a horizontal section taken on line 5—5 of Figure 1.

Figure 6 is an elevational detail of the assembly of the cover and backing plates of a hanger employed on the door.

Figure 7 is a horizontal section taken on line 7—7 of Figure 6.

Figure 8 is a plan detail of a roller housing.

Figure 9 is an elevational detail of a roller housing.

Referring to the embodiment of the invention illustrated in the drawings, the numeral 10 designates a metallic door having a panel 10a provided preferably with a plurality of horizontally extending corrugations 11 and a corrugation 12 adjacent the lower edge of the door and of somewhat less extent than the corrugations 11 so as to leave flat portions in said panel be-

tween the ends of the corrugation 12 and the vertical margins of the door. The door is adapted to be supported for sliding movement upon a track 13 so as to close an opening customarily provided in the side of a railway house car. The door is of the type known as lift door which, in lowered position, is adapted to have frictional engagement with the track 13 in order to prevent sliding movement of said door. Mechanism is provided on this type of door adapted, upon operation thereof, to elevate the door so as to bring about disengagement between said door and the track and support upon antifriction means, whereby the door may be moved in the desired direction.

Lifting mechanism heretofore employed for this purpose which utilizes an actuating bar, particularly where said lifting mechanism has been employed upon metallic doors, were so designed that the actuating bar was positioned upon the outside of the door. In this position of the actuating bar it is apparent that while said bar is effective for its intended operation it is subject, because of such position, to possible injury. No design or construction of lifting mechanism utilizing such a bar has, as far as can be ascertained, permitted said bar to be protected in its operative position without, possibly, the addition of extra parts. The instant novel arrangement, however, is believed to provide a construction and arrangement whereby the actuating bar may, by economical modification of the door, be protected thereby.

The lifting arrangement of the instant invention is preferably contained between a cover plate 16 and a backing plate 17 so as to constitute therewith a hanger unit. A plurality of hanger units 14—15 are secured respectively adjacent the lower corners of the door to the said flat portions. The cover plate 16 and the backing plate 17 of the hanger unit 14 are provided with aligned bearings 18 and 19, respectively, within which the roller housing 20 of the lifting arrangement is adapted to be eccentrically journaled by means of the trunnions 21 and 22. The roller housing 20 is provided with aligned bearings 23 and 24 adapted to receive a pin 25 upon which a roller 26 is rotatably mounted. The cover plate 16 is provided with a flange 27 adjacent one end thereof and with a parallel flange 28 offset from the flange 27 adjacent the opposite end thereof. The backing plate 17 is provided with flanges 29 and 30 adapted to engage the flanges 27 and 28, respectively, provided on the cover plate 16 to which the flanges 29 and 30 are adapted to be

secured. It is clear from the foregoing arrangement of the cover and backing plates that the roller housing with its roller mounted therein is adapted to be journaled between the backing and cover plates and that said plates are then adapted to be secured together so that the hanger may be formed as a unit prior to its attachment to the door. The roller housing is provided with a boss 31 extending preferably from one side of the roller housing adjacent one corner thereof. This boss 31, in addition to its function hereinafter set forth, overlaps the backing plate in the hanger assembly to serve as a stop, limiting the angular displacement of the roller housing within the hanger. Extending from the cover plate 16 is an end portion 32 conforming to and adapted to overlap the adjacent end of the lower corrugation 12 formed in the door for a purpose which will hereinafter appear. The foregoing description of the hanger assembly has been directed to the hanger 14 secured to the lower left hand corner of the door. It is to be understood that this description is applicable to the hanger 15 secured adjacent the lower right hand corner of the door with the exception that the portion of said hanger corresponding to the portion 32 of hanger 14 extends to the left as viewed in Figure 1, while the portion 32 of the hanger 14 extends to the right. Furthermore, since in the preferred embodiment of this invention an operating lever which is employed in the lifting mechanism is mounted adjacent the forward edge of the door the hanger 15 is not provided with an open bearing corresponding to the bearing 18 formed in the cover plate 16 of the hanger 14 and the roller housing assembled with the hanger 15 is not provided with a trunnion corresponding to trunnion 21 which is journaled in the bearing 18 and extends beyond the cover plate. It is to be understood, however, that if the operating lever is mounted upon the right hand hanger 15 said hanger will be modified in accordance with the construction of the hanger 14 to provide for the mounting of the operating lever.

Simultaneous operation of the roller housings provided in each of the hangers is desirable and is effected by means of an actuating bar 33, the ends of which are provided with openings adapted to receive the boss 31 provided on the roller housings. As heretofore indicated, it is desirable that such bar be protected to avoid injury thereto. In the instant invention the bar lies mainly behind the door so as to be protected thereby. More specifically, the bar 33 is positioned within the corrugation 12 provided adjacent the lower edge of the door. To permit engagement of the ends of said bar with the roller housings the ends of the corrugation 12 are coped or cut out to permit extension of said ends of the bar through the ends of the corrugation. The exposed ends of the bar are protected against injury by the portion 32 on the hanger 14 and the corresponding portion on the hanger 15. These portions, as heretofore noted, conform to and overlap the adjacent ends of the corrugation 12.

An operating lever 34 is employed to effect elevation of the door. This lever is mounted upon the trunnion 21 extending from the roller housing 20 through the cover plate 16. As clearly shown in Figure 9 of the drawings opposite portions of said trunnion are cut away as indicated at 35 and 36, whereby said trunnion is adapted to extend into a correspondingly formed opening in the operating lever 34 to effect rotation of the roller housing upon movement of the lever. The

lever is provided with a journal portion 37 adapted to be received within the bearing provided by the opening 38 formed in the cover plate through which the trunnion 21 of the roller housing extends. For this purpose it is to be noted that the trunnion 21 is of less dimension than the opening 38 formed in the cover plate. By this arrangement the operating lever may be set into the hanger, reducing the extension of said lever outwardly from the door and thereby avoiding projection of said lever beyond the tunnel clearance line.

No securing means, such as rivets, connect the lever to the trunnion in the construction above defined. To retain said lever upon the trunnion the cover plate 16 is provided with a flange 39 extending substantially parallel and in spaced relation to the cover plate. This flange 39 in conjunction with the cover plate adjacent thereto and the flange 40 provided around the opening 38 formed in the cover plate provide a recess for the reception of a flange 41 formed on the operating lever 34. It is to be noted that with the arrangement described, the flange 41 of the operating lever is interlocked within the recess provided by the flanges 39 and 40 and the adjacent portion of the cover plate. A quadrant 42 is secured to the door and is engaged between the operating lever proper and a spaced flange 43 provided on said lever whereby said lever is properly guided in its operating movement. Said quadrant is provided with shoulders 44 and 45, the latter of which may serve as a stop to limit the downward movement of the operating lever. It is to be observed that the operating lever may be assembled with its corresponding hanger before said hanger is applied to the door and that after such assembly the movement of the operating lever is such that disengagement between the flanges 39 and 40 provided respectively on the hanger and on the lever is prevented.

It may be pointed out that the actuating bar 33 connected to the roller housings may be further protected in its position within the corrugation 12 by means of a cover plate 46 extending across said corrugation as disclosed in Figure 4 of the drawings. It is to be observed, furthermore, from this figure that the ends of the actuating bar are flattened so as to facilitate engagement between the openings in said flattened ends and the bosses 31 provided on the roller housings.

It is believed to be apparent from the foregoing that the actuating bar 33 is completely protected by the door without necessitating the addition of further elements to said door. It is obvious, furthermore, that numerous changes and modifications in the embodiment disclosed will occur to those skilled in the art without departing from the spirit of the invention disclosed. It is intended, therefore, that all such changes and modifications be comprehended within the invention, which is to be limited only by the scope of the claims appended hereto.

I claim:

1. In combination, a slidable car door having a metallic panel, a hanger secured adjacent each lower corner of said door, said hangers comprising a cover plate, a backing plate, a roller housing eccentrically journaled between said plates and a roller rotatably mounted in said housing, a bar connecting said housings for simultaneous operation, said bar lying mainly inwardly of said panel and the end portions of said bar lying outwardly of said panel and behind said cover plates, one of said housings having a hub extending

through an opening formed in its corresponding cover plate, and an operating lever mounted upon said hub; said lever being journaled in the opening formed in said cover plate.

5 2. In combination, a slidable car door having a metallic panel, a hanger secured adjacent each lower corner of said door, said hangers comprising a cover plate, a backing plate, a roller housing eccentrically journaled between said plates and a 10 roller rotatably mounted in said housing, a bar connecting said housings for simultaneous operation, said bar lying mainly inwardly of said panel and the end portions of said bar lying outwardly of said panel and behind said cover plates, 15 one of said housings having a hub extending through an opening formed in its corresponding cover plate, and an operating lever mounted upon said hub, and means carried by said cover plate overlapping said lever to prevent removal thereof 20 from said hub.

3. In a railway house car having a door opening, a slidable door for closing said opening, said door comprising a panel, a plurality of spaced lifting devices secured directly upon a portion 25 of said panel on the outside of said panel and means connecting said devices for simultaneous operation, said means being positioned upon the inside of said panel.

4. In a railway house car having a door opening, a slidable door for closing said opening, said door comprising a panel, a plurality of spaced lifting devices secured directly upon a portion of said panel on the outside of said panel and a connecting bar for said devices positioned inwardly of said panel, the ends of said bar extending outwardly of said panel and connecting said elevating devices for simultaneous operation.

5. In a railway house car having a door opening, a slidable door for closing said opening, said door comprising a panel, a plurality of spaced lifting devices mounted upon the outside of said panel and a longitudinally movable bar positioned inwardly of said panel, the ends of said bar extending outwardly of said panel and connecting said lifting devices for simultaneous operation.

6. In a railway house car having a door opening, a slidable door for closing said opening, said door comprising a panel, a plurality of spaced lifting devices mounted upon the outside of said panel, a longitudinally movable bar positioned inwardly of said panel, the ends of said bar extending outwardly of said panel and connecting said lifting devices for simultaneous operation and means secured to said panel for covering said lifting devices and said outwardly extending ends of the bar.

7. In a slidable metallic door, in combination, a panel, an outwardly extending horizontal corrugation formed in said panel adjacent an edge thereof having open ends, lifting devices secured to the outside of said panel adjacent the ends of said corrugation, a bar lying in said corrugation, the ends of said bar extending through the ends of said corrugation to the outside of said panel and connecting said devices for simultaneous operation.

8. In a slidable metallic door, in combination, a panel, an outwardly extending horizontal corrugation formed in said panel adjacent an edge thereof having open ends, lifting devices secured to the outside of said panel adjacent the ends of said corrugation, a longitudinally movable bar lying in said corrugation, the ends of said bar extending through the ends of said corrugation

to the outside of said panel and connecting said devices for simultaneous operation.

9. In a slidable metallic door, in combination, a panel, an outwardly extending horizontal corrugation formed in said panel adjacent an edge thereof having open ends, lifting devices secured to the outside of said panel adjacent the ends of said corrugation, a bar lying in said corrugation, the ends of said bar extending through the ends of said corrugation to the outside of said panel and connecting said devices for simultaneous operation, and means secured to said panel for covering said devices and said ends of the bar.

10. In a railway house car, a slidable door having a metallic panel, a hanger comprising a lifting device and a cover plate secured to said door adjacent each lower corner and projecting outwardly thereof, a bar connecting said lifting devices for simultaneous operation, said bar lying upon the inside of said panel with the ends thereof extending to the outside of said panel and behind said cover plates, an operating lever engaging one of said lifting devices, said lever and the adjacent cover plate having interlocking relationship to prevent disengagement of said lever from said lifting devices.

11. In a railway house car, a slidable door, a lifting device secured to said door adjacent each lower corner thereof, means for covering said lifting devices, a bar connecting said lifting devices for simultaneous operating, an operating lever engaging one of said lifting devices, said lever and adjacent covering means having interlocking relationship to prevent disengagement of said lever from said lifting device.

12. In a railway house car, a slidable door, a lifting device secured to said door adjacent each lower corner thereof, means for covering said lifting devices, one of said lifting devices having a trunnion extending through an opening in adjacent covering means, an operating lever mounted upon said trunnion, said lever and said covering means being provided with flanges having interlocking engagement to prevent disengagement of said lever from said trunnion and means connecting said lifting devices for simultaneous operation.

13. In a slidable metallic door, in combination, a metallic panel, a horizontal corrugation formed in said panel adjacent the lower edge thereof and terminating within the vertical margins of said door to leave flat portions between said margins and the ends of said corrugation lying in the main plane of said panel, lifting devices secured to said flat portions, a bar lying in said corrugation, the ends of said bar extending through openings formed in said corrugation and connecting said lifting devices for simultaneous operation.

14. In a slidable metallic door, in combination, a metallic panel, an outwardly extending horizontal corrugation formed in said panel adjacent the lower edge thereof and terminating within the vertical margins of said door to leave flat portions between said margins and the ends of said corrugation lying in the main plane of said panel, lifting devices secured to said flat portions, a longitudinally movable bar lying in said corrugation, the ends of said bar extending through openings formed in the ends of said corrugation to the outside of said panel and connecting said lifting devices for simultaneous operation.

15. In a railway house car, a slidable door, a lifting device secured to said door adjacent each lower corner thereof, means for covering said

- lifting devices, one of said lifting devices having a trunnion extending through an opening in the adjacent covering means, an operating lever mounted upon said trunnion, a boss provided on 5 said lever journaled in said opening in the covering means, said lever and said covering means being provided with flanges having interlocking engagement to prevent disengagement of said lever from said trunnion and means connecting 10 said lifting devices for simultaneous operation.
16. In a railway house car, a slidable door, a lifting device secured to said door adjacent each lower corner thereof, means for covering said lifting devices, one of said lifting devices having a 15 trunnion extending through an opening in the adjacent covering means, an operating lever

mounted upon said trunnion, a boss provided on said lever journaled in said opening in the covering means and means connecting said lifting devices for simultaneous operation.

17. In combination, a slidable car door having a metallic panel, a hanger secured adjacent each lower corner of said door upon the outside of said panel, each of said hangers comprising a cover plate, a backing plate, a roller housing eccentrically journaled between said plates and a roller 10 rotatably mounted in said housing, a bar connecting said housings for simultaneous operation, said bar lying mainly inwardly of said panel and extending behind said cover plates and means for actuating said roller housings. 15

GABRIEL MADLAND.
